UNITED STATES PATENT OFFICE

GRANVILLE A. HUMASON, OF HOUSTON, TEXAS

COMBINED CASING HEAD AND BLOW-OUT PREVENTER

Application filed March 13, 1930. Serial No. 435,404.

This invention relates to new and useful improvements in a combined casing head and blow out preventer.

One object of the invention is to provide a device of the character described specially designed for use in connection with well drilling operations, particularly in the drilling of oil wells where gas pressure is liable to be encountered and is of such construction as to form a tight joint between the drill stem or other inner pipe and the casing or outer pipe so as to prevent the escape of fluid from the well around said inner pipe.

Another object of the invention is to provide in a device of the character described, a packing sleeve which may be readily inserted into the bowl of the casing head around the inner pipe and automatically locked therein, by releasable locking means provided for the purpose and having a slip spider associated therewith to receive pipe engaging slips to support the inner pipe suspended in the well.

A still further feature of the invention is to provide a blow out preventer of the character described which is of such a construction that a drill stem, tubing or other inner pipe and the couplings thereof may be readily passed therethrough in lowering or with drawing said inner pipe.

With the above and other objects in view, this invention has particular relation to certain novel features of construction, operation and arrangement of parts, an example of which is given in this specification and illustrated in the accompanying drawings wherein:

Figure 1 shows a side elevation of a preferred form of the device shown partly in section.

Figure 2 shows a cross sectional view thereof and

Figure 3 shows a side elevation partly in section of a modified type thereof.

Referring now more particularly to the drawings wherein like numerals of reference designate similar parts in each of the figures the numeral 1 designates a casing in a well bore to the upper end of which the tubular bowl 2 of the casing head is con-

nected. This bowl has the flow lines 3 which are controlled by conventional valves (not shown). Above the flow lines the bowl has an internal annular downwardly tapering seat 4.

In the preferred form of the invention there is a packer sleeve 5 formed of rubber or other similar material and anchored to the lower end of which there is an annular metal ferrule 6 whose lower end is beveled to conform to the shape of and to fit against the seat 4. Anchored to the upper end of the sleeve 5 there is an annular ferrule 7 which is extended upwardly forming the slip spider 8 having the upwardly flared seat 9 and provided with the external annular shoulder 10 at its upper end. This spider has the external upwardly pitched ratchet teeth 11 and mounted in opposite sides of the casing head bowl are the radially movable dogs 12 which are attached to the outwardly extending stems 13. These stems work through the reversely arranged inner and outer cap like bearing members 14, 15. Coil springs 16 surround said respective stems and are interposed between the respective outer bearing members 15, and the external abutments 17 on said respective stems. There are also the arcuate flat spring 18 interposed between the inner bearing members 14 and the opposing dogs 12. These springs are effective to hold the respective dogs in engagement with the opposing teeth of the corresponding spider.

Between the external shoulder 10 of the spider 8 and an opposing internal shoulder 19 in the bowl 2 there are located a plurality of adjusting rings 20 for a purpose to be hereinafter stated.

In the form shown in Figure 3 the lower ferrule 6' is of sufficient inside diameter to permit the couplings of the inner pipe to pass therethrough and the upper ferrule 7' is extended downwardly to form a sleeve like housing 21 whose lower end is screwed onto the lower ferrule and between these ferrules there is clamped a plurality of annular rubber rings as 22 designed to fit closely around the inner pipe but which are sufficiently yieldable to permit the couplings of the inner pipe

to pass therethrough in lowering said pipe into or withdrawing it from the well. In this form of the device the spider 8' is substantially similar to the spider 8 having the inside 5 upwardly flared slip seat 9 therein and the external annular shoulder 10 designed to rest directly on the internal annular shoulder 19 of the casing head bowl. In this type of the device the spider 8' has the external 10 teeth and the bowl is provided with the dogs 12 to engage said teeth mounted as, and for the purpose, hereinabove explained. The inner pipe is indicated by the numeral 23 and its sections are connected by the couplings as 15 24 hereinabove referred to. The pipe holding slips designed to be seated in the spider seat 9, for a purpose to be hereinafter stated are indicated by the numeral 25. These slips are tapered downwardly and have the inside 20 pipe engaging teeth and are substantially of the conventional construction.

In carrying on drilling operations the slips 25 will be removed and the unit embodying the packing sleeve 5 will be mounted on the 25 drive bushing of the rotary table by means of which the drill stem is rotated with the bowl 2 located preferably underneath the derrick floor. In case a blow out is threatened said drive bushing may be removed and the 30 packing sleeve assembly dropped down through the rotary table onto the seat 4 around the drill stem or inner pipe 23 and the dogs 12 will engage with the teeth of the spider 8 and thus secure said unit within said 35 bowl. The upward pressure of the fluid in the well against the lower ferrule 6 will expand the packing sleeve 5 and usually prevent the escape of said fluid. If, however, fluid should escape, the slip 25, may be inserted in the spider seat 9 and then the drill 40 stem then lowered and the weight thereof will further expand said sleeve to prevent any leakage. The downward movement of the spider 8 relative to the bowl 2 and the 45 pressure thereof exerted against the sleeve 5 may be regulated by the number of rings 20 provided for that purpose.

When the well is under control, a suitable 50 Christmas tree connection as 26 may be attached to the upper end of the bowl for the purpose of connecting the well known flow connection or what is commonly known as a Christmas tree thereto.

The form shown in Figure 3 will be most 55 frequently used when the pressure within the well is not great, and when it is desired to elevate or lower the inner pipe or tubing and at the same time confine the outward 60 flow of fluid to the outlet lines 3.

When it is desired to remove the packing 65 sleeve units or assemblies after the well is under control the slips 25 may be lifted out and the dogs 12 disengaged from the corresponding spider by an outward pull on the

rods 13 and the packing sleeve assemblies then lifted out.

The drawings and description disclose what is now considered to be preferred forms of the invention by way of illustration only 70 while the broad principle of the invention will be defined by the appended claim.

What I claim is:—

A casing head and blow out preventer including a tubular bowl connected to the upper end of an outer pipe in a well bore and having an inside seat and an outlet beneath said seat, a sleeve like packing in said bowl and seated on said seat, said packing being shaped to surround an inner pipe and having an expandable element and its upper end being formed into a spider having a slip seat, pipe engaging slips in said slip seat, and releasable interengaging means between the bowl and packing and effective to retain the packing in the bowl, said interengaging means comprising teeth on the spider and a yieldably mounted dog in the bowl engageable with said teeth.

In testimony whereof I have signed my name to this specification.

GRANVILLE A. HUMASON.
